POLISHED ROD CLAMP

Kenneth N. Mills, Tulsa, Okla., assignor to Bethlehem Steel Company, a corporation of Pennsylvania

Application January 8, 1942, Serial No. 426,041

13 Claims. (Cl. 24—249)

My invention relates to gripping means for firmly holding suspended metal rods, and more particularly to a hinged or book type polished rod clamp for use in connection with the pumping of deep oil wells.

In the usual method of pumping a petroleum well by a pump actuated by a string of sucker rods, the so-called polished rod is a short top section of the string which is round and highly polished in order to reciprocate through the stuffing box without causing undue wear thereto. The load of the well is transferred from the polished rod to the beam hanger of the surface pumping unit by a gripping device known as a polished rod clamp, which must be very rugged and strong, with a firm and positive grip, yet with a minimum of parts and easy to install and remove.

A common source of accidents, which it is necessary to avoid, is the construction of polished rod clamps with arms or other protuberances projecting from the body far enough to strike a passing workman while the well is being pumped.

As the polished rod clamp must carry the entire well load of several tons without marring the smooth surface of the polished rod, it is a very difficult part to make. One of the hardest problems to overcome is the slipping of the polished rod clamp on the polished rod.

One object of my invention, therefore, is to provide a strong and rugged clamping device.

A further object is a clamp which is simply constructed and easy to install.

Another object is a clamp which is safe and free from hazardous projections.

Still another object is a clamp which will hold the polished rod firmly, without damage and without slipping.

Numerous other objects, purposes and advantages of my invention will be apparent from the following description, wherein reference is made to the accompanying three sheets of drawings illustrating the invention and wherein like numerals of reference indicate like parts.

Figure 1 is a top plan view of the preferred form of my polished rod clamp showing the inserted polished rod in operative position;

Fig. 2 is a section taken on the line 2—2 of Fig. 1, but omitting the polished rod to show more clearly the slanting, superposed slotted prongs for gripping the polished rod;

Fig. 3 is a side elevation of the clamp with the polished rod again inserted;

Fig. 4 is a section taken on the line 4—4 of Fig. 1 with the polished rod omitted;

Fig. 5 is a section of one of the halves of the

clamp taken on the same section as Fig. 2 showing in detail the slotted prongs;

Fig. 6 is a top plan view of a modification of the clamp shown in Fig. 1 with a pivoted eye bolt and headed coupling pin;

Fig. 7 is a section taken on the line 7—7 of Fig. 6;

Fig. 8 is a top plan view of another modification of the clamp;

Fig. 9 is a section taken on the line 9—9 of Fig. 8; and

Figs. 10 and 11 show a further modification of the clamp shown in Fig. 1 with the slotted prongs made normal to the axis of the polished rod, Fig. 10 being a top plan view and Fig. 11 a section taken on the line 11—11 of Fig. 10.

In the preferred form of my invention shown in Figures 1 to 7, inclusive, the body of the polished rod clamp consists of two sections or grips 1 and 2, of cast steel or the like, hinged together on hinge pin 3 with sufficient intervening space when closed to give a firm grip on rods of different sizes, and provided with hollow substantially straight-walled interior chamber 4.

The clamping surface proper of each section of the body comprises a series of superposed somewhat elastic steel prongs 5 in said interior chamber 4, which prongs 5 are directed at an upward angle to the axis of the polished rod 6, which fits into the central opening of the assembled clamp and are integral with the side walls of their respective body sections at their base ends. The outer ends of the prongs 5 are machined to present a smooth arc-shaped surface in contact with the polished rod 6, and the prongs themselves are relatively free to deflect and tighten in their hold when they are loaded in a plane parallel to the axis of said polished rod.

In Figures 1 to 7, inclusive, and in Figures 10 and 11, the side edges of the prongs 5 are not attached to the body of the polished rod grip and permit considerable freedom of deflection. Where a more rigid structure is desired, however, the type of prongs 7, shown in Figures 8 and 9, circularly bored out of the solid block by a revolving cutting tool or the like, may sometimes be preferred.

The angle of the prongs is not especially critical. Prongs 5 in Figures 1 to 7, and prongs 7 in Figures 8 and 9, are at angles about 15° from the horizontal, or about 75° to the vertical axis of the polished rod, but prongs of other inclinations, and even horizontal prongs, may be used, prongs 8 in Figures 10 and 11, for instance, being horizontal prongs. These prongs 5, 7 and 8 must,

however, be of substantial thickness and some degree of stiffness to be able to support the full weight of the reciprocating rod string without risk of marring the rod deeply or of failing rapidly in service. What is a proper prong thickness will depend on such factors as the composition of the steel and the size and weight of the rod, but commonly one-half the radius of the rod, or about $\frac{3}{8}$ -inch in the usual case, will be ample.

The individual sections 1 and 2, in Figures 1 to 5 and 8 to 11, inclusive, are secured together by a bolt or bolts 9 each having a head 10 and lock washer 11 and nut 12 thereon, whereas in Figures 6 and 7, each of said washers and nuts fastens on an eye bolt or eye bolts 13 connected to body half 1 with a second hinge pin 14 and engaging a slot 15 in the other body section 2. Hinge pins 3 and 14 may each be provided with a head of any conventional type, as for instance the round button heads 16 and 17 shown in Figures 6 and 7, or may be unheaded and drive-fitted, as in the other figures. Elevated strengthening flanges or ribs 18 and boss 19 are refinements of design which may be regarded as optional features.

To install the clamp shown in Figures 1 to 5, inclusive, said clamp is placed about the polished rod 6 and the nuts 12 are screwed onto bolts 9, drawing the prongs 5 into contact with the polished rod 6. The other types shown are similarly installed. As the prongs are located at a right angle or an acute angle to the axis of the polished rod, they will bend slightly when the grip is tightened up. This deflection will cause them to exert an uneven force on the polished rod, and the greater part of the force will be exerted on the lower side of the clamping surface. When a load is applied to the polished rod, it will tend to cause the prongs to deflect in the opposite direction to that caused by tightening the clamping bolts, and this contrary deflection will cause the prongs to exert an increased and balanced force on the polished rod. As the magnitude of this clamping force increases with the applied load, the polished rod clamp will not slip, and as the deflections of the prongs are small, it will not mark the polished rod to an unsatisfactory extent.

It will be noted that although the clamp is hinged to facilitate installation, none of the stress is carried on the hinge itself. All the stress is taken by the gripping prongs in the body of the clamp, and thereby a full length positive grip is assured.

While I have shown and described my invention in considerable detail, I do not wish to be limited to the exact and specific details so shown and described, and I may use any or all such substitutions, modifications, or equivalents thereof, as are embraced within the scope of the invention, or are pointed out in the appended claims.

Having thus described my invention, what I claim as new and useful and desire to secure by Letters Patent is:

1. A rod suspending device comprising arcuate body sections hinged to admit a rod centrally therein, a plurality of separate resilient gripping members therein having smooth arcuate inner margins to hold the rod without substantially marring the same, bolts joining the body sections, and nuts threadedly engaging the bolts for tightening the body sections about the rod.

2. A rod clamp comprising a metal block

formed of two sections, each having a side wall and having a central opening to receive a rod, yieldable integral gripping members having smooth inner faces in each section between the side wall and the rod to hold the rod, a hinge joining the two sections in the rear portion thereof, and bolts provided with nuts and extending through apertures in the forward portion for bolting the sections together.

10. 3. A rod clamp comprising a pair of rod gripping metallic members each having a side wall, a plurality of smooth arcuate contact surfaces integral with the side walls and adapted to grip on opposite sides of a rod, and clamping bolts for connecting the pair of gripping members together.

4. A rod clamp comprising a metal block formed of two sections hinged together and having a central opening to receive a rod, opposing aligned horizontal slots cut in the walls of said opening forming integral annular prongs with smooth inner faces to permit a better grip on the rod, and transverse bolts for clamping the sections onto the rod.

25. 5. A rod clamp comprising arcuate metal body members hinged to admit a rod, inclined grooves positioned radially in said sections producing ribs having smooth arcuate inner margins to assist in gripping the rod, eye bolts hinged to one of the body members and engaging the other member, and nuts on the bolts for tightening the body members about the rod.

6. A rod clamp comprising arcuate hollow hinged members, smooth faced prongs therein 35 normal to the vertical axis of a rod and contoured to receive and hold the rod without marring said rod, and transverse bolts provided with nuts for tightening the prongs about the rod.

7. A rod clamp comprising arcuate hollow 40 hinged members, a plurality of superposed flat slanting prongs having smooth arcuate inner margins to grip a rod therein without substantially marring the same, eye bolts pivoted to one of the hinged members and passed through the other member, and nuts threaded onto the eye bolts for tightening the prongs about the rod.

8. A rod clamp comprising arcuate hollow 45 hinged members, a plurality of integral resilient prongs having smooth arcuate inner faces for gripping a rod firmly therein, said prongs being inclined at an angle to the vertical axis of the rod, eye bolts pivoted to one hinged member and passed through the other member, and nuts threaded onto said eye bolts for tightening the 55 hold of the prongs on the rod.

9. A rod clamp comprising arcuate metal body members hinged to admit a rod, integral smooth-faced arcuate clamping prongs therein to hold the rod in a fixed position, and transverse bolts 60 provided with nuts for tightening the clamping jaws onto the rod.

10. A polished rod clamp comprising a pair of arcuate hinged metallic half members, a plurality of fitted gripping prongs having smooth arcuate inner margins inside each half member integral therewith and inclined upwardly toward the vertical axis of a polished rod to resist and support the load thereof, and transverse bolts for tightly bolting the half members together to secure said polished rod.

11. A polished rod clamp comprising arcuate metallic body members hinged to admit a polished rod, integral pronged means having smooth inner faces for gripping the polished rod therein 75 without substantially marring the same, and

clamping means for tightening the hinged body members about the rod.

12. A polished rod clamp comprising hinged metallic body members having a central opening to admit a polished rod, integral arcuate prongs having smooth inner faces projecting inwardly toward the center of the polished rod to grip and hold said polished rod without substantially marring the same, and transverse bolts provided with nuts for tightening the grip of the teeth on said 10 polished rod.

13. A polished rod clamp comprising a block formed of two hinged metallic body members and having a central opening adapted to receive a polished rod, a set of individual arcuate prong members in each body member adapted to grip and hold said polished rod, and transverse bolts for bolting the body members together to clamp said prong members against the polished rod.

KENNETH N. MILLS.
